CARBURETOR

Emil Schimanek, Muegyetem, Budapest, Hungary

Application January 31, 1935, Serial No. 4,253
In France February 1, 1934

10 Claims. (Cl. 261—48)

Object of the invention is a carburetor in which the float chamber is replaced by a fuel-pressure reduction regulator. Such a carburetor shall also comply with the demands which are required of the carburetor in certain particular cases, especially in aviation which requires carburetors which warrant a regular fuel supply in all positions of the aircraft in the air and independently of centrifugal forces and the like.

10 The carburetor according to the invention warrants such a constant fuel supply to the fuel orifice or nozzle, whatever the conditions of flight and the pressure variations of the supplying source may be.

15 The invention consists in that the fuel supply to a calibrated opening or nozzle of the carburetor is regulated by means of a movable member, such as for instance a slider, the movement of which is determined by a system of two membranes or diaphragms with different surface areas, which are subjected, on the one side, with their adjacent surfaces to the, preferably constant partial vacuum on which the admission of the air is dependent, and on, the other side, to the constant pressure of the fuel.

Fig. 1 shows the carburetor carried out according to the invention in vertical section, and Fig. 2 a partial section through another modification.

The body 1 of the carburetor is provided with 30 an air inlet 2, and a discharge passage 3 for the combustible mixture which is connected with the inlet of the motor. By means of the throttle valve 4, the power of the motor can be regulated.

In the upper part of the carburetor body 1 a cylinder 6 is arranged in which a piston 7 is movable which is pushed downward by a spring 10 thus acting in the same direction as the weight of the piston. This piston 7, according to its position in the cylinder 6, closes up more or less 35 an opening 11 which forms the communication between the space 37 of the combustible discharge socket 3 and the space 41 of the air inlet 2. At the bottom of the piston 7 a needle 5 is attached in such a manner that it is adjustable 40 as to its height. This can be accomplished, for instance, by screwing the threaded end 8 of the needle into a corresponding thread in the bottom of the piston and securing it by nut 9. The 45 needle 5 extends through a channel in the body 1 of the carburetor which channel is provided with two cylindrical enlargements 15 and 47 communicating with each other through a calibrated opening 12. The needle 5 passes through this 50 opening and closes it up more or less with its

conical part 5a, according to the height-position of the piston 7.

A conduit 42' opens into the upper part 47 of the channel at its lower end adjacent the calibrated opening 12, which conduit communicates through openings 42 with the space 37 of the discharge passage 3. Further, the cylindrical part 47 of the channel opens through its upper open end into the space 41 of the air inlet.

The pressure reduction regulator is constructed 10 as follows:

In the cylindrical part 15 a tube-like slider 14 is slidably arranged and supported by two diaphragms 16 and 16', the surfaces of which have different areas. These diaphragms are fastened 15 in a bell-shaped lower part of the carburetor body 1.

The fuel is supplied by means of a pump or from a higher located reservoir or from a reservoir under pressure, through the conduit 13 to 20 the carburetor, via the cylindrical part 15 of the same, into the upper part 23 into which a conduit or channel 19' opens at one end and terminates at its other end in a socket 19 serving as 25 over-flow for the fuel.

As can be seen from the drawing, the slider 14, at the same time, governs the fuel supply through the conduit 13 and the outflow of the surplus of the fuel through the conduit 19'. The length of the slider 14 is such that the fuel only 30 can flow through the conduit 13 and the opening 22 in the slider into the interior of the slider and into the calibrated opening 12 when the conduit 19' to the over-flow is shut off.

At the lower end of the slider 14 a cylinder 25 35 is arranged which is closed by a bottom 25a and in which a piston 26 with valve-flaps 27 is slidable. By this means a braking or damping for the movement of the needle system is provided. A conduit 31a between the sockets 31 connects 40 the space 32 between the two diaphragms with the space 39 between the cover of the cylinder 6 and the piston 7, while another conduit between the sockets 35 and 36 establishes the communication between the space 34 beneath the larger 45 diaphragm 16' and the space 41 of the air inlet 2. By reason of this construction there exists the same partial vacuum above the piston 7 and in the space 32 between the diaphragms, and the same pressure below the piston 7 and below the 50 larger diaphragm 16'.

The carburetor operates as follows:

When the motor is at rest the pressure in the space 32 between the two diaphragms is just the same as the pressure in the spaces 34 and 24, 55

below the larger and above the smaller diaphragms respectively, is equal to atmospheric pressure when the two diaphragms are in their position of rest as shown in Fig. 1.

5 When the motor is running, the partial vacuum in the space 37, is communicated through the hole 38 to the space 39 over the piston 7 whereupon the piston is raised, uncovering the opening 11 to a corresponding extent so that 10 the air can flow to the motor in the direction of the arrow 40.

The difference between the pressures which exist, on the one hand, in the space 39 above the piston 7 and, on the other hand, below the 15 piston 7, has just the required magnitude in order to balance the weight of the piston 7 augmented by the pressure of the spring 10 and the weight of the parts connected to the piston. The pressure of the spring is substantially constant owing to a sufficiently great number of 20 windings which form the spring. Under these conditions the difference in pressure between the space 41, on the one side, and the spaces 39, 37, on the other side, will be constant, whatever 25 the load and the number of revolutions of the motor may be. Therefore, the air will always flow under the influence of the same pressure-difference through the carburetor in the direction of the arrow 40.

30 When the load or the number of revolutions of the motor increases, the piston 7 will rise higher and higher, and a greater amount of air can flow through the carburetor under the same pressure-difference, that is with the same 35 velocity.

The air takes the following two ways: firstly, one way through the pre-carbureting stage, by 40 which the air enters from the space 41 in the direction of the arrow 43 into the interior of the central channel 47 and mixes there, flowing in the direction of the arrow 45, with the fuel coming 45 out of the calibrated opening;—and secondly, another way in the direction of the arrow 40, by which the air from the space 41 mixes with the mixture coming through the openings 42 and thereby thoroughly whirls it through.

The velocity of the air current through the channel 47 may be regulated by changing the entrance-area of the same, for instance by inserting rings 48 with different inner diameters.

The fuel reaches by the following path the calibrated opening 12: The partial vacuum in the cylinder space 39 above the piston 7 is communicated through the conduit 31a to the space 55 55 32 between the two diaphragms 16 and 16'. Since the diaphragm 16' is greater than the diaphragm 16, the slider 14 is lifted and thereby first closes the over-flow conduit 19' and then opens the fuel supply conduit 13 as soon as the holes 22 are in 60 alignment therewith.

The pressure of the fuel in the space 24 increases till it preponderates, whereby the diaphragm 16' is pressed downwards so that the slider 14 tends to shut off the fuel supply. Thereupon a balance position of the slider ensues, whereby the fuel pressure is regulated to a constant pressure which can be pre-determined. Under this constant pressure the fuel reaches the calibrated opening 12 at the other side of 70 which a partial vacuum exists which has also a constant value.

On starting the motor the level of the fuel rises to the height indicated at 49, corresponding to the height of the over-flow conduit 19.

75 As soon as the motor is normally running, the

fuel is fed through the calibrated opening 12 in consequence of the constant pressure-difference mentioned above.

When the motor comes to a standstill the partial vacuum in the space 32 disappears; the slider sinks and, after having shut-off the fuel supply conduit, opens the over-flow conduit 19', whereby the space 23 is put under atmospheric pressure.

The braking or damping cylinder 25 connected 10 to the diaphragm 16 has the following task: If the throttle valve 4 is rapidly opened the motor starts again, and the partial vacuum in the space 39 above the piston 7 instantaneously rises. This increase of the partial vacuum tends to 15 suddenly lift the piston 7, which movement the piston 26 (provided with valves) at the lower end of the needle 5 tends to counteract in forcing upwards the fuel contained in the space 30. This pressure is transmitted to the upper cover 20 of the cylinder space 30 and effects the lifting thereof and therewith that of the slider 14, whereby, on the other hand, the opening of the fuel supply conduit 13 is further opened and, on the other hand, the pressure in the space 25 23 is raised. This has the effect that a larger amount of the fuel passes through the calibrated opening 12, so that a very effective re-starting of the motor can be attained.

Such an effect of the piston 26 does not occur 30 if the piston moves downwards, because thereby the valve-claps open entirely and the fuel can flow without resistance through the piston provided with the valves.

Moreover, the braking which the piston 7, 35 when sinking, experiences by the damping, though only to a small extent, tends to force the slider 14 downwards and to partially shut off the fuel supply conduit 13, whereby the retarding of the motor is favoured.

In the modification of the carburetor according to the invention shown in Fig. 2, the over-flow conduit 19' of Fig. 1 has been omitted, and the interruption of the fuel supply is effected by the needle by means of its particular formation, 45 one portion 55 of the needle taking over the function of a clap or a valve. This portion becomes seated with its lower surface on a seat 51 and thus shuts off the calibrated opening 12.

While the motor is running the needle 5 is 50 lifted and the valve portion 55 is raised from its seat so that the fuel can flow through the opening 12. The slider 14, in this case, regulates the fuel supply solely through the conduit 13.

It is to be understood that modifications in 55 particulars of the construction may be designed without departing from the spirit of the invention. In particular, a throttle valve 4' may be placed in the air inlet 2 and either the valve 4 or the valve 4' may be omitted if desired.

60 What I claim is:

1. In a carburetor for an internal combustion engine, an air inlet, a fuel inlet, a fuel chamber, a mixing chamber, a nozzle between the fuel inlet and chamber, a device for regulating 65 the fuel supply through said nozzle, said device including diaphragms having pressure surfaces of different sizes to produce a differential action, the diaphragm having the smaller size pressure surface being subjected on one side to the 70 pressure of the fuel in the fuel chamber and forming a wall of said chamber and being subjected on its other side to the partial vacuum set up by the engine.

2. A carburetor comprising a main housing 75

having an air inlet, a fuel inlet, a fuel chamber, a mixing chamber, a passage from said mixing chamber to the engine and a device for regulating the flow of fuel to said mixing chamber, 5 said device including a cylindrical casing on the top of the housing, a tubular member adapted to cut off communication between the fuel inlet and the fuel chamber, another cylinder carried on the lower end of the tubular member and in 10 communication with the fuel chamber, a piston in said first cylinder under the influence of a spring in said cylinder chamber, a stem depending from said piston, another piston at the lower end of said stem movable in the second cylinder, 15 an auxiliary housing carried on the lower end of the main housing, spaced diaphragms dividing said auxiliary housing into upper, lower and intermediate compartments, the upper compartment being in communication with the fuel inlet, the intermediate compartment being in communication with the passage leading to the engine and the lower compartment being in communication with the air inlet, said diaphragms having pressure surfaces of different sizes where- 20 by they are actuated by varying pressure conditions. 25

3. In a carburetor, a main casing having an air inlet, a fuel inlet, a fuel chamber, a mixing chamber and an outlet to the engine for the 30 mixture, a tubular member for controlling the flow of fuel to the mixing chamber, an auxiliary casing fixed to the lower end of the main casing, spaced diaphragms fixed to the tubular member dividing said latter casing into upper, lower and 35 intermediate compartments, one of said compartments being in communication with the air inlet, another of said compartments being in communication with the suction side of the engine, and another of said compartments being in 40 communication with the fuel inlet and forming part of the fuel chamber and a piston under the influence of the suction of the engine for partially controlling the flow of air and fuel.

4. In a carburetor, a main casing having an 45 air inlet, a fuel inlet, a fuel chamber, a mixing chamber and an outlet to the engine for the mixture, a tubular member for controlling the flow of fuel to the mixing chamber, an auxiliary casing fixed to the lower end of the main casing, spaced diaphragms fixed to the tubular member 50 dividing said latter casing into upper, lower and intermediate compartments, one of said compartments being in communication with the air inlet, another of said compartments being in 55 communication with the suction side of the engine, and another of said compartments being in communication with the fuel inlet and forming part of the fuel chamber, a piston under the influence of the suction side of the engine for 60 partially controlling the flow of air and fuel and means for damping the movement of said piston, said means including a piston on the lower end of the stem of the first named piston and movable in the fuel. 65

5. A carburetor comprising a main casing having an air inlet, a fuel inlet, a fuel chamber, a mixing chamber and a passage from said mixing chamber to the engine, an auxiliary casing fixed to the bottom of the main casing, mechanism 70 for regulating the flow of fuel to the mixing chamber including a movable tubular member having openings adapted to align with the fuel inlet, a pair of pressure responsive diaphragms fixed to said tubular member at spaced intervals 75 for dividing said auxiliary casing into upper,

lower and intermediate compartments, one of said diaphragms having a larger pressure surface than the other diaphragm, said upper compartment being in communication with the fuel chamber, said intermediate compartment being 5 in communication with the engine passage and said lower compartment being in communication with the air inlet, mechanism for partially regulating the flow of air and fuel to the engine passage including a chamber disposed between the air inlet and engine passage and being in constant communication with said passage, a piston movable in said latter chamber and normally closing communication between the air inlet and engine passage, a spring loaded on said piston 15 to keep it in normal position, a stem depending from said piston and extending into the air chamber below the larger diaphragm and adapted to curtail the flow of fuel to the mixing chamber, a chamber formed in the lower end of the 20 movable tubular member and being in communication with the fuel chamber, a piston on the lower end of said stem and movable in said last named chamber against the fluid pressure for damping the movement of the first piston. 25

6. A carburetor comprising a body having an air inlet, a fuel inlet, a mixing chamber, a nozzle for the fuel, a fuel pressure regulating member including a slider and spaced diaphragms having pressure surfaces of different sizes for 30 effecting the action of said slider, the movement of said diaphragms being influenced by the difference between the partial vacuum prevailing in the carburetor and atmospheric pressure, said member being adapted to keep constant the fuel 35 pressure in front of the nozzle and means for varying said partial vacuum.

7. In a carburetor, an air inlet, a fuel inlet, a mixing chamber, a nozzle disposed between the fuel inlet and chamber, a device for regulating 40 the fuel supply through said nozzle, said device including spaced diaphragms having pressure surfaces of different sizes to produce a differential action, the pressure surfaces on one side of said diaphragms being subjected to partial 45 vacuum, and one of said surfaces on the other side of one of said diaphragms being subjected to fuel pressure, the other of said diaphragms being subjected on its opposite side to a pressure greater than the pressure between said spaced 50 diaphragms.

8. A floatless carburetor comprising an air inlet, a fuel inlet, a nozzle for the fuel, a pressure regulating member for the fuel in front of said nozzle, an automatic throttling device disposed 55 in said air inlet and dividing said air inlet into two spaces, said throttling device being influenced on the one hand by the atmospheric pressure prevailing in the space of the air inlet in front of the throttling device and on the other 60 hand by the under pressure prevailing in the space of the air inlet behind said throttling device caused by the suction of the engine and means for imparting said difference in pressure between said spaces to said pressure regulating 65 member for the fuel, said pressure regulating member being actuated by said pressure difference.

9. A floatless carburetor as claimed in claim 8 in which the throttling device comprises a piston 70 acted upon on the one side by the atmospheric pressure prevailing in the space in front of the throttling device and on the other side by the under pressure prevailing in the space behind the throttling device and in addition thereto by a 75

constant spring pressure whereby a variation of the pressure difference on both sides of the piston causes the piston to throttle more or less the passage between both said spaces thereby reestablishing a constant pressure difference in both said spaces.

10. A floatless carburetor according to claim 7 in which the device for regulating the fuel supply through the nozzle is actuated by a constant pressure difference, said constant pressure difference being obtained by an automatic throttling device disposed in the air inlet and dividing said air inlet into two spaces, said throttling de-

vice being influenced on the one hand by the atmospheric pressure prevailing in the space of the air inlet in front of the throttling device and on the other hand by the under pressure prevailing in the space of the air inlet behind said throttling device caused by the suction of the engine thereby keeping constant the difference between the pressures prevailing in the said spaces and means for imparting said constant pressure difference to said device for regulating the fuel supply through said nozzle. 5

EMIL SCHIMANEK.
